Patented Mar. 28, 1922.

UNITED STATES PATENT OFFICE.

JAMES BRUCE MASON, JR., OF NASHVILLE, TENNESSEE.

LEAD PENCIL.

1,411,116.

Specification of Letters Patent. Patented Mar. 28, 1922.

Application filed April 30, 1921. Serial No. 465,658.

To all whom it may concern:

Be it known that I, JAMES BRUCE MASON, Jr., a citizen of the United States, residing at Nashville, in the county of Davidson and State of Tennessee, have invented certain new and useful Improvements in Lead Pencils, of which the following is a specification.

This invention relates to lead pencils of the kind in which the lead is contained within a casing and is propelled or fed when required through a suitable guide and through a pointed end or nozzle in such manner that the outer end of the lead shall project only a short distance beyond the tip of the nozzle so that while sufficiently exposed for writing purposes it is not apt to break.

According to this invention spare leads are contained within a magazine divided into compartments surrounding the longitudinal axis of the pencil and which is so constructed that when the tip of the pencil is removed from the barrel, the leads will be exposed and can be readily withdrawn. When a lead is worn out it may be easily discharged from the pencil and a new lead placed in working position. The lead in use is fed forwards by a pusher rod provided with a nut which engages a threaded tube within the barrel and which extends through a slotted tube which may be rotated in such manner as to move the pusher rod back and forth as required. The lead is pushed through a guide tube which grips it and holds it firmly. The parts above described are at the lower or outer end of the pencil barrel. In the upper end I provide a chamber for an erasive rubber which is held in position by a clamping device and the outer end of which is covered by a removable cap. Other features of the invention will be hereinafter described.

In the accompanying drawings:—

Figure 1 shows a longitudinal central section through a pencil embodying my improvements.

Figures 2 and 3 are on an enlarged scale, Figure 2 being a section on the line 2—2 of Figure 1 and Figure 3 being a section on the line 3—3 of Figure 1.

Figure 4 is a perspective view of the cylinder containing a chamber in which the erasive rubber is held and the slotted tube within which the pusher rod operates.

Figure 5 is a perspective view showing particularly the manner in which the leads

project from the magazine when the tip or pointed end of the pencil is removed.

Figure 6 is a detail view in elevation of the split guide tube for the lead within the point of the pencil.

Figure 7 is a perspective view of the pusher rod and its nut.

The barrel A of the pencil may be made of suitable metal or other material. It is internally threaded at its lower end to receive the threaded end b of the pencil tip or point B. The tip is thus made detachable from the barrel. At its upper end the barrel carries a collar C which has a flange c crossing the end of the barrel. This collar is loosely connected with the barrel so that it may be turned thereon. Within this end of the barrel is located a cylinder D containing a chamber for a stick of erasive rubber E. The collar C is firmly connected with the outer end of this cylinder at d and beyond this point the cylinder is continued and externally screw threaded as indicated at e where it is engaged by a nut F. The outer threaded portion of the cylinder is slotted as shown at e' so that when the nut F is applied, it will clamp the rubber and hold it securely. By loosening the nut, the rubber may be moved outwards when worn and again adjusted and held. A cap G is applied to the nut F having a sliding connection therewith. It serves to protect the outer end of the rubber and keep it clean. The cap may be readily removed when it is desired to use the rubber. The cylinder D extends inwards to the middle portion of the barrel and is formed with a closed end h having a central opening in which is firmly secured in any suitable way a slotted tube H which extends nearly to the outer or lower end of the barrel. This tube is of considerably less diameter than the bore of the barrel, leaving a space around it serving as a leads magazine which is divided into a plurality of compartments i by radial partitions I which may be separately applied and secured in place or may be formed integrally with the cylinder by milling out recesses or compartments in a tube of sufficient size. There are slots h' in the opposite sides of the tube H as indicated. These slots extend from the upper end of the tube as indicated in Figure 1 to near the bottom thereof as indicated in the same figure. The slots are closed at opposite ends and are diametrically opposite to each other. Surround-

100
105
110

ing the slotted tube H is a cylinder K which is internally threaded. This tube is stationary, the partitions I being formed on or securely fastened to it and the outer ends of 5 the partitions engaging tightly the barrel A. The leads in the various figures are indicated at L and when a lead is in working position as indicated in Figure 1, it is engaged by a pusher rod M which is provided with a 10 nut N which extends through the slots h' of the tube H and engages the threads of the tube K. The lower end of the tube H carries a collar n which is keyed to it as shown and it bears against the lower end of the 15 threaded tube K. When the collar C is turned in the proper direction, the cylinder D is also turned and through the connections shown the slotted tube H is turned, thereby turning the nut N of the pusher rod and the 20 pusher rod is made to advance and push the lead through the tip. By reversing the movement of the collar C, the pusher rod may be moved inwards to make room for a new lead or to permit the lead in use to be 25 pushed back into the pencil.

When a lead is worn out, the tip B may be unscrewed and withdrawn from the barrel as indicated in Figure 5, the pencil being first reversed. When the tip is thus 30 moved, the spare leads L will project from the magazine and one of them may be extracted, then the new lead may be inserted through the guide tube O and properly positioned. This guide tube O is slotted at o 35 and has a slotted head o' having a slot or kerf o² to receive a tool. This screw threaded head is seated in a block P fastened in the pencil tip and having a threaded opening p' to receive the head o' of the guide 40 tube. It will be observed that the lower slotted end of the guide tube abuts against the inclined inner walls of the tip B so that by forcing the guide tube inwardly or outwardly it may be made to grip the lead to a 45 greater or less extent. This adjustment of the guide tube is made before a lead is inserted in it, but when this adjustment is once perfected for leads of a given size no further adjustment is usually necessary.

50 The pencil thus constructed is very simple in construction and is easily operated. It may be made at small expense. It is provided with a rubber eraser of large size which will last a long time. The leads are 55 held individually so that they are not apt to be broken and when a new lead is desired, the operation of merely taking off the tip and securing a lead is very simple. The leads are exposed as indicated in Figure 5 60 so that when their ends are uppermost they

may be easily withdrawn from the magazine.

I claim as my invention:

1. A lead pencil, comprising a barrel, a rotatable cylinder within the upper portion 65 of the barrel, a slotted tube attached to said cylinder and rotatable therewith, a pusher rod within the tube and having a nut extending through the slots, and a threaded tube which the nut engages which surrounds 70 the slotted tube and which is of materially less diameter than the barrel to provide a storage space for leads between it and the barrel.

2. A lead pencil, comprising a barrel, a 75 rotatable cylinder within the upper end of the barrel, a collar rotatably mounted on the barrel and firmly attached to said cylinder, a slotted tube rotatably mounted in the barrel and attached to said cylinder, a pusher 80 rod within said slotted tube, a nut carried thereby extending through the slots of the tube, and a threaded tube surrounding the slotted tube and engaged by the nut which is of materially less diameter than the interior bore of the barrel to provide a storage space for leads between it and the barrel.

3. A pencil, comprising a barrel, having a removable tip provided with means for 90 guiding a lead when in use and with means for propelling the lead through the tip, and a magazine for spare leads having inner and outer walls surrounding the propelling means and divided into individual compartments for the lead which are of less length than the leads and are of less length than the inner wall of the magazine.

4. A pencil, comprising a barrel having a detachable tip having inclined inner walls, a 100 block fixed inside the tip and having a threaded central opening, and a guide tube for the lead slotted at one end and threaded at the other, the threaded end engaging said block, and the slotted end engaging the inclined inner walls of the tip.

5. A pencil, comprising a barrel, a removable tip carried by the barrel, a guide-tube in the tip for the lead, and a magazine for spare leads surrounding the longitudinal 110 central axis of the barrel and which is divided into a plurality of compartments by rigid partitions which terminate within the outer ends of the leads in the magazine whereby ends of the leads project from the 115 magazine and can be easily handled.

In testimony whereof, I have hereunto subscribed my name.

JAMES BRUCE MASON, JR.
